UNITED STATES PATENT OFFICE

PAUL BELLAVANCE, OF ATTLEBORO, MASSACHUSETTS, ASSIGNOR TO LOUIS STERN COMPANY, OF PROVIDENCE, RHODE ISLAND, A CORPORATION OF RHODE ISLAND.

CHAIN

Application filed February 28, 1930. Serial No. 432,075.

This invention relates to a chain of the type used for watch bracelet straps and the like; which are constructed to present an ornamental appearance; and has for its object to provide an easily assembled chain which will be durable in construction, and which will have the so-called basket weave appearance.

A further object of the invention is to prevent lateral movement of the assembled section on the connector member without the use of solder or additional parts.

With these and other objects and advantageous features in view, the invention consists of a novel arrangement of parts more fully disclosed in the detailed description following, in conjunction with the accompanying drawings, and more particularly set forth in the appended claims.

20 In the drawings:

Fig. 1 is a top plan view of the section of chain constructed in accordance with this invention;

Fig. 2 is a bottom view thereof with the frame-shaped members shown in dotted lines;

Fig. 3 is a perspective view of one of the frame members;

Fig. 4 is a perspective view of one of the sections;

30 Fig. 5 is a perspective view showing the section shown in Figure 4 as folded into finished position;

Fig. 6 is a perspective view of a blank which may be used as a connector section, if desired, by being folded as illustrated in Figure 5;

Fig. 7 is a perspective view showing one portion of one of the sections as folded about the frame member and the other portion as 40 opened out;

Fig. 8 is a perspective view illustrating the manner of assembling the parts;

Fig. 9 is a perspective view showing some of the parts assembled and others in the 45 process of being assembled.

It is found desirable to form band chains without the use of solder with links or sections having a staggered parallel relationship which is conveniently referred to in the 50 trade as a "basket weave" appearance; and

in order to accomplish this result, I have provided a frame link and wrapped about the lateral edges of such a link sheet metal sections with their edges notched and inturned so that the cut out or notched portion will 55 receive the longitudinally extending portion of the frame member and prevent lateral movement in either direction of this section upon the member, which locking also serves the further function of securing the connecting links and other sections which are intermediate the end sections of the frame link from disengagement therefrom and holding the entire construction in assembled relation; and the following is a detailed description of 60 the present embodiment of this invention illustrating the preferred means by which 65 these advantageous results may be accomplished:

With reference to the drawings, 10 designates the frame member or link having an opening 11 therein, leaving portions 12 extending laterally of the chain and a portion 13 extending longitudinally thereof. This frame member is split as at 14, for convenience in threading the sections thereon, as presently described.

A section 15 is folded into band form with its meeting edges 16 notched as at 17 and turned inwardly as shown in Figure 5. This band-shaped section is positioned upon the unsplit lateral edge of the frame member 10, as shown in Figure 7, with its notch 17 receiving the longitudinally extending portion 13 of this member, whereby the section will 80 be prevented from movement in either direction laterally of the bracelet.

In connecting up the chain, after a band-shaped section is secured at the lateral edge 90 of the frame member as mentioned, two sections are threaded through the split 14 one over each of the laterally extending portions 12 of the frame member, as illustrated in Figure 8, and also over a similar portion 12 95 of the next link, after which a section which I designate 18 is threaded over both of the lateral portions 12 of the frame member, as illustrated in Figure 9, etc., until the final or marginal edge section 19 is positioned so 100

that the notch 17 will engage the longitudinal portion 13 at the split end of the frame member, as is shown in Figure 9.

I have described the above chain as though formed from sections all of which are provided with notches 17 in their ends, but it will be apparent that only the band sections which embrace the lateral edges of the frame member need be notched as the notches in the other sections serve no purpose I may, therefore, use a plain unnotched section 20, as illustrated in Figure 6, which is folded in the same form as shown in Figure 5 for these sections intermediate the two lateral edge sections of the connecting member.

The split 14 allows the portions 12 of the frame member to be moved out of the plane one with the other to permit the sections to be threaded over these portions 12.

20 It will be apparent that links may be connected and the chain built up by suitably threading the laterally extending portions 12 in one link through the sections of the next or in other convenient manner until the chain of the desired length is produced.

While I have described certain construction forms which embody the principles of my invention, it is obvious that other desired changes in arrangement may be made within 25 the spirit and the scope of the invention as defined in the appended claims.

I claim:

1. In a chain for a bracelet or the like, a member having an opening therein with side 30 portions extending longitudinally of the chain and end portions extending laterally thereof, a sheet metal section folded about the lateral edges of said member with its ends turned inwardly and notched to receive the side portion of said member.

40 2. In a chain for a bracelet or the like, a member having an opening therein with side portions extending longitudinally of the chain and end portions extending laterally thereof, a band-shaped section at each lateral edge of said member having its ends turned inwardly and notched to receive the side portions of said member for preventing lateral movement of said section on said member in either direction, and link sections intermediate said sections encircling the end portions of adjacent members for hingedly joining said members together.

3. In a chain for a bracelet or the like, a member having an opening therein with side 50 portions extending longitudinally of the chain and end portions extending laterally thereof, a band-shaped section at each lateral edge of said member, a recess in said section receiving a portion of said member for preventing lateral movement of said section on said member in either direction, link sections intermediate said sections encircling the end portions of adjacent members for hingedly joining said members together, and an addi-

tional intermediate band-shaped section between said link sections.

4. In a chain for a bracelet or the like, a member having an opening therein with side portions extending longitudinally of the chain and end portions extending laterally thereof, a band-shaped section at each lateral edge of said member having its ends turned inwardly and notched to receive the side portions of said member for preventing lateral movement of said section on said member in either direction, link sections intermediate said sections encircling the end portions of adjacent members for hingedly joining said members together, and an additional intermediate band-shaped section between said link sections.

In testimony whereof I affix my signature.

PAUL BELLAVANCE.
